(57) **CLAIM**

We claim the ornamental design for a sausage conveyor hook, as shown.

DESCRIPTION

FIG. 1 is a right elevational view of a sausage conveyor hook showing my new design;

FIG. 2 is a left elevational view thereof;

FIG. 3 is a top plan view thereof;

FIG. 4 is a bottom plan view thereof as seen from the left-hand side of FIG. 1;

FIG. 5 is a front elevational view; and,

FIG. 6 is a rear elevational view as seen from the right-hand side of FIG. 1.
